ATTORNEY

UNITED STATES PATENT OFFICE.

EDWIN B. ADAMS, OF SPRINGFIELD, MASSACHUSETTS.

INHALER.

SPECIFICATION forming part of Letters Patent No. 350,711, dated October 12, 1886.

Application filed October 14, 1885. Serial No. 179,878. (No model.)

To all whom it may concern:

Be it known that I, EDWIN B. ADAMS, a citizen of the United States, residing in Springfield, in the county of Hampden and State of Massachusetts, have invented new and useful Improvements in Inhalers, of which the following is a specification, reference being had to the accompanying drawings.

My invention relates more particularly to improvements in instruments for administering anaesthetics.

The object of my invention is to produce a simple, cheap, and easily-operative device, which shall be free from the objectionable features found in many of the inhalers now in use; and to that end my invention consists in the construction and arrangement herein set out, whereby the beneficial objects of my invention are attained.

20 In the accompanying drawings, in which like letters of reference indicate like parts, Figure 1 is a longitudinal vertical section. Fig. 2 is a view as seen from the front or face end of the device. Fig. 3 is a perspective, and Fig. 25 4 is a view of a cap for the partial closing of the shell.

Referring now to the drawings in detail, *a* indicates a cylindrical case or shell of metal, open at one end, and having the partitions *b c* situated at the opposite end, as shown. The space between these two partitions is divided by a partition, *d*. The partition *e* has two openings provided with valves *e* and *f*, the valve *e* being adapted to open outward or toward the patient to allow the vapor or gas to pass from the sponge chamber to the patient, to be inhaled. The valve *f* is adapted to open outward or away from the patient, allowing the exhalation to pass into the chamber *g*, which 35 chamber is provided with an outlet or opening, *j*, to allow the exhalation to escape. The valves are nicely adjusted, so that they will be operated by the current produced by the breathing of the patient. A face-shield or hood, *k*, of rubber or other semi-rigid material, having its edges shaped to approximately conform to the contour of the face, is secured to the end of the shell *a*, and is preferably held in place by a clasp or band, *l*, passing around the shell *a*, and held in place with a screw, *m*. In addition to the hood *k*, I provide an auxiliary hood,

n, of a much softer and more pliable material than the principal hood *k* which I attach to the hood *k* in such manner that the edge of the auxiliary hood projects beyond the edge of the hood *k*. The principal hood, *k*, gives the requisite rigidity, while the soft pliable projecting auxiliary hood *n* gives the desired softness to enable the hood to conform readily to any face without discomfort to the patient.

55 The opening from the sponge-chamber to the compartment *h* is covered with a cap, *o*, having openings in its sides, thus avoiding the possibility of any fluid passing through, which might occur were the openings direct.

60 The valve *e* consists of a thin light disk, preferably of hard rubber, and is supported in place by a screw or stud, *p*, which is supported by the cross-bar *r*.

The valve *f* is of like shape and material as 65 the valve *e*, and is supported by a screw or stud, *s*, which in turn is supported by a post, *t*.

The direction of the currents is indicated by the arrows in the drawings.

70 If the device is used for administering ether or other like anesthetics, the sponge is saturated in ether before being placed in the sponge-chamber; or the liquid may be turned in upon the sponge while in place. As the air is drawn in it passes through the saturated sponge and 75 becomes charged with the anesthetic vapor, and passing into the chamber *h*, and thence through the valve *e*, is inhaled by the patient. When, however, the air is exhaled, it closes the valve *e* and opens the valve *f*, allowing it 80 to escape, the operation being automatic.

75 If it is desired to use the device for administering gas or vapor generated or stored in some other chamber, then a cap, *u*, provided with a tube, *v*, is placed over the open end of the 85 shell *a*, and a rubber tube is connected therewith.

It will be seen that with this device the patient will not breathe the same air but once, and that the operation, application, and use 90 of the device is simple and complete.

Having, therefore, described my invention, what I claim, and desire to secure by Letters Patent, is—

95 An inhaler for medicated vapors, consisting, essentially, of a cylindrical shell or casing, *a*, having an opening leading to the exhaling-

chamber, and provided with a face-piece or hood, *k*, an end partition, *c*, arranged across the casing and formed with valve-openings, a partition, *b*, arranged between the end partition and the open end of the casing, and formed with an opening provided with a perforated cover, *o*, a radially-arranged partition, *d*, between the said partitions *b* *c*, to form the chambers *g* *h*, a valve, *e*, to close the opening

in the partition *c* to the chamber *h* from without, and a valve, *f*, to close the opening to the chamber *g* from within, substantially as described. 10

EDWIN B. ADAMS.
